UNITED STATES PATENT OFFICE.

EDWARD B. ALLEN, OF ELIZABETH, NEW JERSEY, ASSIGNOR TO THE SINGER MANUFACTURING COMPANY, A CORPORATION OF NEW JERSEY.

STITCHED BUTTONHOLE.

SPECIFICATION forming part of Letters Patent No. 735,433, dated August 4, 1903.

Application filed September 22, 1902. Serial No. 124,425. (No model.)

To all whom it may concern:

Be it known that I, EDWARD B. ALLEN, a citizen of the United States, residing at Elizabeth, in the county of Union and State of New Jersey, have invented certain new and useful Improvements in Buttonholes, of which the following is a specification, reference being had therein to the accompanying drawings.

10 This invention relates to improvements in buttonholes, and more particularly to eyed buttonholes, which in practicing the invention are barred and finished in a novel manner.

In carrying the invention into effect the body of a buttonhole is or may be stitched around in the usual manner by any purled overseam, and the finished buttonhole is barred by stitches which are formed across the end of the buttonhole and overlaid by other barring-stitches radiating from the end of the buttonhole-slit, these radiating stitches forming a purl at their outer ends, and this purl may be so disposed as to lie in a straight or approximately straightline across the end 25 of the buttonhole or may be disposed in the arc of a circle.

In the accompanying drawings, which are of a diagrammatic character, Figure 1 illustrates a complete buttonhole embodying one 30 form of the invention, but with the purl of the radiating barring-stitches disposed to lie straight across the end of the buttonhole. Fig. 2 is a partial view illustrative of the first part of the buttonhole stitching and barring operation, and Fig. 3 is a similar view illustrative of one form of the completed operation. Fig. 4 is a diagrammatic view illustrative of the preferred form of the completed operation. Fig. 5 is a view similar 35 to Fig. 1, but with the purl of the radiating stitches disposed in the arc of a circle.

Referring to the drawings, *a* denotes an overedge-seam extending about the sides and eye of a buttonhole and the thread or threads 40 of which are concatenated in any suitable or well-known manner to form a continuous purl *b* along the edges of the buttonhole-slit and about the eye of the buttonhole at the inner ends of the overseaming-stitches.

45 Formed across the end of the buttonhole-slit

are what may be termed "crossing" barring-stitches *c*, which are overlaid and tied down by radiating barring-stitches *d*, extending from the end of the buttonhole-slit as a center and radiating outward therefrom.

55

The improved buttonhole preferably comprises two sets of crossing barring-stitches *c* and *c'*, the stitches *c* being formed at the commencement of the stitching operation before stitching the first side of the buttonhole, 60 as denoted in Fig. 2, and the second set *c'* being formed after the last side of the buttonhole has been stitched, but before the radiating barring-stitches *d* are formed, so that in either case the crossing barring- 65 stitches will be overlaid and tied or sewed down by the radiating barring-stitches.

In the diagrammatic drawings the crossing barring-stitches are represented by curved lines for clearer illustration; but as a matter 70 of fact these stitches lie straight across the ends of the buttonholes. Also in the diagrammatic view, Fig. 4, the two sets of crossing barring-stitches are represented as being spread out, so as to occupy different positions, 75 while in the improved buttonholes these two sets of stitches preferably lie in the same plane, one set on top of the other.

The thread or threads of the radiating barring-stitches *d* are so concatenated as to form 80 *c* a purl *e* at their outer ends where the needle punctures and the thread or threads pass through the body of the goods, the seam thus formed making a very straight and peculiarly characteristic bar. When the radiating barring-stitches are so disposed as to form a straight or approximately straight purl, as 85 illustrated by Fig. 1, the inner or slit needle or an overseaming-needle at its inner descents will occupy positions at different distances 90 from the ends of the buttonhole-slit, as illustrated by the diagrammatic view, Fig. 4; but as the stitches are tightened or drawn up they will present much the appearance illustrated by Figs. 1 and 3. Of course all of these 95 stitches required for the completed buttonhole are formed in a piece of fabric *f*, which will preferably be cloth or leather.

The improved buttonhole is preferably made by a buttonhole-stitching mechanism 100

such as is fully shown and described by my applications, Serial Nos. 24,679 and 113,808, filed, respectively, July 24, 1900, and June 30, 1902, and in which the stitching mechanism travels and performs partial rotary movements and the work-clamp remains stationary, such machines forming overedge and barring stitches which in the concatenation of the threads are all of the same character in that both the overedge and the barring stitches are concatenated to form a purl, by which the inner ends of the overseaming stitches and the outer ends of the radiating stitches are connected. The invention is not, however, to be understood as being limited to any particular style of purl-buttonhole overseam or to any particular stitch-forming mechanism. Also the invention may be embodied in straight buttonholes which are barred at both ends, in which case the buttonholes will of course be worked and barred on straight-buttonhole machines instead of the eye-buttonhole machines above referred to.

Having thus described my invention, I claim and desire to secure by Letters Patent—

1. A fabric having a stitched buttonhole comprising crossing barring-stitches lying across the end of the buttonhole-slit and radiating barring-stitches overlying the said crossing barring-stitches.

2. A fabric having a stitched buttonhole comprising crossing barring-stitches lying across the end of the buttonhole-slit and radiating barring-stitches overlying the said crossing barring-stitches, the thread or threads of the said radiating barring-stitches being concatenated to form a purl at the outer ends of the said barring-stitches where the thread or threads pass through the material.

3. A fabric having a stitched buttonhole comprising two sets of crossing barring-stitches lying across the end of the buttonhole-slit, combined with radiating barring-

stitches overlying the said crossing barring-stitches.

4. A fabric having a stitched buttonhole comprising crossing barring-stitches lying across the end of the buttonhole-slit, combined with radiating barring-stitches overlying the said crossing barring-stitches, the thread or threads of the said radiating barring-stitches being concatenated to form, at their outer ends, a purl which is disposed as a straight line, or approximately so, across the end of the buttonhole.

5. A fabric having a stitched buttonhole comprising two sets of crossing barring-stitches lying across the end of the buttonhole-slit, combined with radiating barring-stitches overlying the said crossing barring-stitches, the thread or threads of the said radiating barring-stitches being concatenated to form, at their outer ends, a purl which is disposed as a straight line, or approximately so, across the end of the buttonhole.

6. A fabric having a stitched buttonhole comprising side stitches connected together at their inner ends by a continuous purl, and a bar comprising stitches lying across the side stitches and similarly connected together at their outer ends by a purl which is on the same side of the work as the purl at the inner ends of the side stitches.

7. A fabric having a stitched buttonhole comprising side stitches connected together at their inner ends by a continuous purl, and a bar comprising radiating stitches similarly connected together at their outer ends by a purl which is on the same side of the work as the purl at the inner ends of the side stitches.

In testimony whereof I affix my signature in presence of two witnesses.

EDWARD B. ALLEN.
